UNITED STATES PATENT OFFICE

144,482

DESIGN FOR A FILTER AND PUMPING APPARATUS

John V. Davis and John S. Hoffman,
Detroit, Mich.

Application June 27, 1945, Serial No. 120,358

Term of patent 14 years

(Cl. D65—1)

To all whom it may concern:

Be it known that we, John V. Davis and John S. Hoffman, citizens of the United States, residing at Detroit, in the county of Wayne and State of Michigan, have invented a new, original, and ornamental Design for a Filter and Pumping Apparatus, of which the following is a specification, reference being had to the accompanying drawing, forming part thereof.

The figure is a perspective view of a filter and pumping apparatus showing our new design.

The other side of the article not shown is substantially like the side shown.

We claim:

The ornamental design for a filter and pumping apparatus, as shown and described.

JOHN V. DAVIS.
JOHN S. HOFFMAN.
